(57) CLAIM

I claim the ornamental design for a deposit container, as shown and described.

DESCRIPTION

FIG. 1 is a perspective view of the deposit container;

FIG. 2 is a front side view thereof;

FIG. 3 is a rear side view thereof;

FIG. 4 is a left side view thereof;

FIG. 5 is a right side view thereof; and,

FIG. 6 is a top side view thereof.

Broken lines, such as those depicting the top of the deposit container shown in FIGS. 1-6, are environmental only and form no part of the claimed design.
